FREDERICK H. OGILVIE, OF JERSEY CITY, NEW JERSEY, ASSIGNOR TO WISNER MANUFACTURING COMPANY, OF NEW YORK, N. Y., A CORPORATION OF NEW YORK.

CLEANING APPARATUS.

1,141,139.

Specification of Letters Patent. Patented June 1, 1915.

Application filed April 28, 1914. Serial No. 334,911.

To all whom it may concern:

Be it known that I, FREDERICK H. OGILVIE, a subject of the King of Great Britain and a resident of Jersey City, in the county of Hudson and State of New Jersey, have invented certain new and useful Improvements in Cleaning Apparatus, of which the following is a specification.

My invention relates to cleaning apparatus; and particularly to apparatus of the kind mentioned, for milk cans and other storage vessels which have to be especially treated after they have been emptied of their contents, to be put in sanitary condition for further use.

The primary object of my invention is to provide a construction which is formed to engage milk cans and the like, in such a manner that they will be retained for a definite period of time; whereby such vessels cannot be withdrawn until the apparatus has thoroughly effected and completed the cleaning operation. To this end I make my apparatus of such size as to accommodate a number of vessels; which are started at one end of the apparatus and removed at the other; after being cleaned and dried at intermediate points.

My invention also includes means at one end which will prevent the withdrawal of a milk can, or similar vessel, after it has once been started, until it has passed successively through the different positions which it must take in order to be treated as required; and by the time it reaches the other end, at which it can be freely removed, all the steps in the operation of cleaning the vessel have been performed, and the desired result has been achieved.

Further objects and advantages of my invention will appear from the following specification taken in connection with the accompanying drawings, the same characters of reference indicating the same parts on all the views.

On said drawings Figure 1 is a side elevation of my apparatus, showing the same broken away at one side to expose the interior; Fig. 2 is a top plan of the same; and Fig. 3 is a vertical transverse sectional view taken on the line 3-3 of Fig. 1.

In the particular description of the drawings, I employ the numeral 1 to indicate the frame work or body of my apparatus, which is mounted upon legs or standards 2. The

frame work as well as the legs 2 are preferably constituted of lengths of angle bars riveted together; and the legs 2 are connected by cross beams at the bottom, forming feet; and braced by bars joining the legs to the frame work 1, in any suitable way. This frame work 1 carries a trough 3 which has closed ends 4, but is substantially open at the top; and in the top is a support upon which the milk cans or other vessels are placed, when it is desired to clean the same. The support mentioned comprises a plate 5, which is of less length than the frame work 1; and is mounted upon cross bars 6, secured to the sides of the frame work 1; the plate being fastened to these cross bars in any suitable fashion. From the ends of the plate to the ends of the frame work 1 extend longitudinal bars 7, which are spaced from one another and form a continuation of the support in the top of the trough, of which the plate 5 is a part. This plate 5 has an opening 8 and two openings 9 through it, and below these openings are nozzles 10. The nozzle 10 in line with the opening 8 delivers water; and the other two nozzles are connected to a source of steam supply. The plate 5 is long enough to accommodate three milk cans or the like at one time; and the holes 8 and 9 are spaced far enough from each other to enable a milk can on the plate 5 to be in inverted position, that is with its mouth down, over each opening when the apparatus is in operation.

As indicated by the broken line circles on Fig. 2, my apparatus is long enough to accommodate three milk cans on the plate 5, another can on the bars 7, at the left of this plate; and two more milk cans on the bars 7 at the other end of the frame work 1. At the end last mentioned, the bars 7 may extend longitudinally from the plate to the frame work 1, along the sides only of the frame work leaving an open space for a steam heating coil 11. This coil is placed below the level of the bars 7 and is carried by transverse straps 12, fastened to the frame work 1, or the sides of the trough 3, at their ends. The bars 7 along the sides of this coil are long enough to accommodate two milk cans after the latter have passed off the plate 5, and as there is no obstruction above the coil 11, heated air will naturally rise into the cans and dry the same.

The pipe which supplies steam to the

heating coil leads through one end of the trough 3; and the other end of the coil is connected to the nozzles 10, below the holes indicated at 9; also the water pipe, which 5 supplies liquid to the nozzle 10 below the aperture 8, enters through the same end of the trough; and this pipe, shown at 13, as well as the pipe leading from the steam coil, may be secured in any suitable fashion in 10 the trough 3.

The nozzles 10 are each provided with valves inside the same, and having external projecting stems 14. These valves normally close the nozzles, and may be kept shut by 15 suitable springs; and each stem 14 is engaged by a bell crank lever 15, pivotally mounted in any suitable fashion adjacent to the stem 14. One arm of each of these levers will extend through the plate 5, which will 20 be recessed to the extent required; and the edges of the arms above the plate may be beveled. As a result when the milk cans are moved along the plate the rims of the mouths thereof will engage the upper arms 25 of these bell cranks and force them downward. The bell cranks will thus force the stems 14 to open the valves and the nozzles and allow these nozzles to discharge into the cans. The nozzle 10 below the aperture 8 30 has a drain cock with handle 17; and the two steam nozzles 10 are connected together by a short length of drain pipe which has a drain cock 18. The trough 3 may be provided at any convenient point with a drain 35 cock 19.

Between any two of the bars 7 at the end opposite that carrying the steam coil 11, I secure a one way movable stop 20 which is mounted in a U-shaped strap 22 secured to 40 the bars 7 and extending below them. This stop is in the form of a lever or pawl; and its spindle 21 may carry a spring which normally holds one end of this pawl down against the strap 22 and the other end above 45 the level of the plate 5. I also arrange along the sides of the plate 5 retaining flanges 24; utilizing angle irons of sufficient length for this purpose; and the retaining flanges are placed far enough apart to allow 50 the mouths of milk cans to be received between them. The front retaining flange is flush at its end adjacent the stop 20 with the corresponding end of the plate 5, but it will extend beyond the opposite end of the plate 55 as clearly shown in Fig. 2. The flange at the rear may run nearly the full distance to the opposite ends of the frame work, but the flange 24 along the front of the apparatus will terminate about at the middle 60 of the heating coil 11 and leave a space along the front edge of the frame work 1 which is large enough to permit a milk can to be withdrawn therethrough; and a curved rail or bar 25, forming a guide, may be secured to the rear and adjacent end of the

frame work 1 to direct the cans by turns off the support through this space, and over the front edge of the frame work 1. The back flange will run the full length of the frame 1 to prevent a can at the left being 70 pushed over the rear edge.

The utility and mode of operation of my apparatus will now be pointed out.

Fig. 2 illustrates, by means of broken circles, the position of the milk cans on the 75 support carried by the frame work 1 in the top of the trough 3, and it will be apparent that my apparatus can accommodate one half a dozen cans, all of which are placed bottom upward on the support comprising 80 the plate 5 and bars 7, at once. Three cans will be on the plate 5 in position to be sprayed out by the nozzles 10; two will rest upon the bars 7 over the heating coil; and another will be carried upon the bars 7 adjacent the stop 20, in readiness to be moved 85 on the plate 5 when the line of cans is moved up, after one is taken off around the opposite end of the front flange 24.

In Fig. 3 I illustrate in broken lines the 90 shape of a milk can at the mouth thereof, and it will be seen that these cans are received between the flanges 24 and retained upon the support until they reach the heating coil 11. When a can is placed upon the 95 bars 7 at the forward edge of the plate 5, the stop 20 allows it to be moved upon the plate over the aperture 8; but after it has passed the stop, it cannot be taken off the apparatus until it has traversed the row of 100 nozzles and passed off the apertured plate 5. Of course, as each can comes over each aperture, it presses down the upper arm of the bell crank associated therewith, and causes the nozzle below the aperture to deliver 105 fluid to its interior. Each can is thus first sprayed with water and then twice with steam. It is next dried by the coil 11 and guided off the apparatus by the rail 25, when the attendant moves it ahead to make 110 room for the cans behind it. A single attendant can operate my apparatus and it will be apparent that he cannot keep the cans moving across the support in the top of the trough too fast for the operation of 115 cleaning to be thoroughly performed. As he takes one off at the right of the apparatus, he must then move the remaining five forward far enough to make room for another at the left; and the removal and replacement of the cans, one at a time, in this way, will insure each can remaining in position to be sprayed first with water and then twice with steam, the required interval in each instance; and the same will be true of 120 the space of time during which each can will remain on the bars 7 above the heating coil 11 to be dried.

The position and length of the rail 25 are such that so long as an integral number 125

of cans, such as two, rest upon the section of the supporting frame work 1 above which the rail is located; that is, directly above the coil 11; the next three cans, when pushed 5 up close behind the first two, will in every case be directly over the nozzles 10. The rail 25 therefore serves not only to cause the cans to pass over the front edge of the apparatus at the delivery end of the same, 10 but also as a device for gaging the proper positions of the cans on the plate 5. In other words, so long as the first can about to come off rests upon the frame work approximately as shown in broken lines in 15 Fig. 2, and the other four are as close to the first as possible, the third, fourth and fifth cans will necessarily be in place to be sprayed by the nozzles, and the attendant will not have to look to see whether the 20 nozzles are actually in operation.

I do not wish to be limited to any particular number of nozzles 10, or to any particular number of cans to be accommodated above the coil 11, after passing off the plate 25 5. Neither do I wish to be restricted to the use of angle iron retainers 24, as in some cases rods or piping spaced above the top of the framework 1 a sufficient distance to allow the rims of the mouths of the cans 30 to slide under them, may be employed.

The operation of my apparatus will therefore, be substantially continuous and a large number of cans can be cleaned with a minimum expenditure of time and labor. In the 35 practice of my invention a skilled dairy man will have no difficulty in keeping the cans moving through the apparatus without lagging in his work and at the same time without pushing them through too rapidly to 40 clean them as thoroughly as the strictest municipal regulations may specify.

From the above description it will be seen that I have produced an advantageous, yet simple construction, to serve my purpose. I do not wish to be limited to the 45 exact structural details herein set forth as the same may be varied within wide limits and I, therefore, reserve the right to make such changes in the shape, size and arrangement of the parts as fairly fall within the 50 scope and spirit of my invention.

Having described my invention, what I believe to be new, and desire to secure and protect by Letters Patent of the United 55 States is:—

1. The combination of means for supporting thereon a plurality of inverted storage vessels having mouths with outward extending rims, retaining means extending 60 along the supporting means to engage the rims of the mouths of said vessels on opposite sides of the same, whereby said vessels cannot be displaced from the supporting means except by movement along the latter, 65 and one or more devices for delivering

cleaning agent to the vessels as they are moved along the supporting means.

2. The combination of means for supporting thereon a plurality of inverted storage vessels having mouths with outward extending rims, a one-way movable stop at one end of said means, retaining means extending away from said stop along the supporting means to engage the rims of the mouths of said vessels on opposite sides of the same, 70 whereby said vessels cannot be displaced from the supporting means except by movement along the supporting means, and one or more devices for delivering cleaning agent to the vessels as they are moved along 75 the supporting means.

3. The combination of means for supporting thereon a plurality of inverted storage vessels having mouths with outward extending rims, angle-iron retainers extending 80 along the supporting means to engage the rims of the mouths of the said storage vessels on opposite sides of the same, whereby said vessels cannot be displaced from the supporting means except by movement along 85 the latter, and one or more devices for delivering cleaning agent to the vessels as they are moved along the supporting means.

4. The combination of means for supporting thereon a plurality of inverted storage 90 vessels having mouths with outward extending rims, a one-way movable stop at one end of said means, angle-iron retainers extending away from the stop along the supporting means to engage the rims of the mouths 95 of the vessels on opposite sides thereof, whereby said vessels cannot be displaced from the supporting means except by movement along the latter, and one or more devices for delivering cleaning agent to the 100 vessels as they are moved along the supporting means.

5. The combination of means for supporting thereon a plurality of storage vessels, a U-shaped strap transversely mounted on 110 said means and carried below the same, a pivot carried by the upper part of said strap, a stop movably mounted on the pivot and extending above the level of the supporting means, and resilient means for holding the lower end of the stop against the 115 bottom of the strap.

6. The combination of means for supporting thereon a plurality of inverted storage vessels having mouths with outward extending rims, retaining means extending along said means to engage the rims of said mouths on opposite sides thereof, whereby said vessels cannot be displaced from the supporting means except by movement 120 along the latter, one or more devices for delivering cleaning agent to said vessels as they are moved along the supporting means, and a rail carried by the supporting means 125 beyond said devices, the distances between 130

1 said devices corresponding to the size of said vessels, and the section of said supporting means adjacent said rail being of sufficient extent to accommodate an integral 5 number of said vessels, whereby said rail may serve to gage the correct positions of said vessels with respect to said devices.

7. The combination of means for supporting thereon a plurality of inverted storage 10 vessels having mouths with outward extending rims, a one-way movable stop at one end of said means, a drying coil at the other end of said means, a plurality of devices for delivering cleaning agent to said vessel located 15 between said stop and said coil, retaining means extending along the supporting means adjacent said devices to engage the rims of said mouths on opposite sides of the same, whereby the vessels cannot be dis-

placed from the supporting means except by 20 movement over said devices, and a rail carried by the supporting means above said coil, the devices being spaced apart according to the size of said vessels, and the section of said supporting means adjacent said rail and coil being of sufficient extent to accommodate an integral number of said vessels, whereby the rail may serve to gage the correct positions of said vessels with respect to said devices. 25

Signed at New York in the county of New York and State of New York this 6th day of April A. D. 1914. 30
